Primary Examiner — Raphael Barkai(74) *Attorney, Agent, or Firm* — Morgan, Lewis & Bockius LLP(57) **CLAIM**

The ornamental design for a television receiver with computer, as shown and described.

DESCRIPTION

FIG. 1 is a perspective view of a television receiver with computer showing our new design;
FIG. 2 is a front view thereof;
FIG. 3 is a rear view thereof;
FIG. 4 is a left side view thereof;
FIG. 5 is a right side view thereof;
FIG. 6 is a top plan view thereof;
FIG. 7 is a bottom plan view thereof; and,
FIG. 8 is a rear perspective view thereof.
The broken lines show unclaimed subject matter only and form no part of the claimed design.
